ASPARAGUS WASHER

Clyde W. Hoon, Rio Vista, Calif.

Application June 27, 1939, Serial No. 281,381

6 Claims. (Cl. 146—81)

This invention relates to asparagus washing machines, and particularly represents improvements over the washer shown in my copending application for patent, Ser. No. 141,499, filed May 8, 1937 and which became Patent No. 2,197,978 on April 23, 1940.

The principal object of the present invention is to simplify and at the same time improve the device employed for holding down the asparagus while it is being cut and washed, and which will function with equal efficiency whether it engages a single layer of asparagus or a stack of the same.

The construction and mounting of the rotary asparagus supporting table itself is also simplified and improved over that of the original apparatus.

I have also provided an improved spray pipe arrangement.

These objects I accomplish by means of such structure and relative arrangement of parts as will fully appear by a perusal of the following specification and claims.

In the drawings similar characters of reference indicate corresponding parts in the several views:

Figure 1 is a top plan view of the improved washer.

Figure 2 is a fragmentary sectional elevation along the washing tunnel, as on line 2—2 of Fig. 1, but drawn as though the structure followed a straight rather than a curved path.

Figure 3 is a fragmentary enlarged radial section on line 3—3 of Fig. 1.

Referring now more particularly to the characters of reference on the drawings, the supporting framework of the machine comprises horizontal crossing beams 1 mounted a suitable height from the floor, and supporting an upstanding circular band 2 disposed adjacent the outer end of the beams.

The rotary table which is supported on the frame comprises a deep, endless circular band 3 of large diameter, riding on flanged rollers 4 mounted on the band 2. A short distance above its lower edge, arms 5 are rigidly secured on and project radially out from the band 3. These arms support a plurality of relatively small shallow bands 6, disposed in spaced and concentric relation to each other and to band 3. The upper edges of bands 6 are all on the same level, so as to form an asparagus supporting grate; such level being a considerable distance below the top of band 3, which forms a back stop for the tips of the asparagus stalks supported on the table in substantially radiating relation thereto. An intermediate pair of the bands 6 are more widely spaced than the remainder, as plainly shown in Fig. 3, the radially innermost band 6a of said pair cooperating on its outer edge with a rotary disc cutter 7. This cutter is mounted on a shaft 8 extending radially of the table above the band 3, and journaled in a fixed position on the frame

in any suitable manner. An electric motor 9, supported on the frame preferably radially in from the table, is connected to the shaft 8 in driving relation, as in the previous apparatus.

5 The table is rotated at a suitable speed by means of another motor 10 mounted on one of the frame beams 1 radially inward of the table and connected by a belt drive 11 or otherwise with a pinion 12 disposed a short distance ahead of 10 the cutter 7 relative to the direction of rotation of the table. This pinion meshes with an inverted ring gear 13 secured on the radially inner face of the band. By reason of the construction and mounting of the table as above described it will be seen that the band 3 forms the backbone of the table, from which the latter is both supported and driven, and hence need be the only relatively heavy member of the structure. As a result, the asparagus supporting portion of the table, which carries only a small load at any point, may be made much lighter than was the case with the previous structure without any sacrifice of necessary strength.

25 The cutter 7, and a portion of the table both ahead of and beyond the same, are enclosed by an arcuate tunnel 14 mounted on the frame. A water pipe 15 extends along the tunnel below the top and at its radially inner side. A number of downwardly directing spray pipes 16 are connected to pipe 15 by means of double swivel fittings 16a. The spray pipes may thus be swung to extend across the tunnel at different angles so as to spray over different radial distances or at different angles relative to a horizontal plane, or 30 they may be turned about their axes so that the sprays may be directed downwardly at different angles to the perpendicular. In this manner asparagus stalks of any length may be efficiently washed.

35 40 Another spray pipe 17 extends along the tunnel below the table and is arranged to direct sprays upwardly onto the asparagus between bands 3 and 6a. A third spray pipe unit, indicated at 18, may be mounted in the tunnel at its radially outer side and below the top, to direct sprays down onto the butt portions of the stalks, should this be desired.

45 Disposed in the tunnel ahead of the cutter 7 and near the top and radially inner side of the tunnel, is a vertically positioned sprocket wheel 19, whose diameter is considerably less than the distance from the top of the tunnel to the table. An endless chain 20 passes about the sprocket and extends substantially the full length of the 50 tunnel as shown in Fig. 2. It may here be noted that while the chain is shown conventionally, 55 actually it is a special though standard swivel type, capable of flexing in both horizontal and vertical directions.

60 The upper run of the chain is kept above spray

pipes 16 and prevented from sagging and also caused to follow the curvature of the tunnel by means of a fixed supporting track 21 which curves down at its end opposite the sprocket as shown at 22. The lower run of the chain normally rides on one of the table bars 6, and is caused to substantially follow the curvature of the tunnel by means of roll 23 rigid with and projecting laterally from certain links of the chain to engage the band 3. The chain is quite heavy, in order that its slack portion shall exert the necessary pressure on the asparagus, rather than from any load requirements.

Additional hold-down pressure on the chain and asparagus adjacent the cutter is had by means of an idler roller 23 riding the lower run of the chain between the cutter and sprocket wheel, and mounted on an arm 24 extending to a point beyond the cutter and pivotally mounted in the tunnel.

The total length of the chain is thus obviously much greater than twice the straight-line distance from the sprocket to the curved end of the track 21, or in other words has a considerable amount of slack. At the same time, the amount of slack is such that between the sprocket and the table, the chain extends at an acute angle to the table as shown rather than depending straight down.

As a result of this arrangement, a substantially V-shaped space is provided between the table and chain, so that the asparagus advancing with the table, whether in a single layer or stacked, can lift and pass under the adjacent portion of the chain; the roller of course lifting at the same time.

In order to drive the chain at a speed synchronized with that of the table, and so that its lower run travels in the same direction as the table, an endless chain 25 is connected in driving relation with the sprocket 19 outside the tunnel, one run of said chain engaging a sprocket pinion 26 fixed coaxially with pinion 12.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In an asparagus trimming apparatus which includes a horizontally movable table for the support of the asparagus to be trimmed, means to move the table in one direction and a relatively fixed cutter cooperating with one edge of the table; a relatively heavy endless chain overhanging the table with its runs in a vertical plane and extending from ahead of to beyond the cutter, elements above the table supporting the upper run of the chain ahead of and beyond the cutter, one element comprising a sprocket and the other including means to prevent sagging of said upper run between its points of support; the length of the chain being such that its lower run depends slack from the supporting element

and normally, for a substantial portion of its length and from a point ahead of the cutter, rides on the table.

2. In an asparagus trimming apparatus, a horizontally movable table for the support of the asparagus to be trimmed, means to move the table in one direction, a relatively fixed cutter cooperating with one edge of the table, a relatively heavy endless chain overhanging the table with its runs in a vertical plane and extending from ahead of to beyond the cutter, a sprocket mounted above and spaced from the table and engaging the chain ahead of the cutter and a track beyond the sprocket supporting and preventing the upper run of the chain from sagging; the length of the chain being such that it depends slack from the sprocket and track so that its lower run normally rides slackly on the table.

3. In an asparagus trimming apparatus, a rotary table for the support of the asparagus to be trimmed, means to turn the table in one direction, a fixed cutter cooperating with one edge of the table, a relatively heavy endless chain whose runs are disposed in spaced horizontal planes and capable of flexing both in horizontal and vertical planes, said chain extending circumferentially of the table in overhanging relation thereto from ahead of to beyond the cutter, a sprocket whose axis is substantially radial with the table engaging the upper run of the chain ahead of the cutter, a supporting and guide track curved concentric with the table supporting the upper run of the chain beyond the cutter, the length of the chain being such that it depends slack from the sprocket and track and its lower run rides slackly on the table, means to turn the sprocket so that the chain is driven and means to maintain the lower run of the chain in a path substantially concentric with the table irrespective of vertical flexing of said lower run.

4. A structure as in claim 3 in which said last named means comprises rods projecting laterally from the chain radially inward of the table and a member concentric with and upstanding from the table and engaged by the outer ends of the rods.

5. In an asparagus trimming apparatus, a rotary driven table for the support of the asparagus to be trimmed, a fixed trimming cutter cooperating with one edge of the table and a device to hold down the asparagus while it is being trimmed by the cutter, said device comprising an endless member disposed with upper and lower runs and capable of flexing both in horizontal and vertical planes, the lower run being adapted to rest on the asparagus and extending circumferentially of the table above the same from ahead of to beyond the cutter, means supporting the member at the ends of its runs and including a driving element and means to maintain the lower run of the member in a path substantially concentric with the table irrespective of vertical flexing of said lower run.

6. An apparatus as in claim 5, in which said last named means comprises elements projecting laterally from said member in spaced relation along the same in a direction radially inward of the table and a smooth faced band concentric with and upstanding from the table and engaged by said elements at their outer end.

CLYDE W. HOON.
